US00D909723S

(12) **United States Design Patent** (10) **Patent No.:** **US D909,723 S**
Girard et al. (45) **Date of Patent:** **** Feb. 9, 2021**

(54) **SHOE**

(71) Applicant: **PUMA SE**, Herzogenaurach (DE)

(72) Inventors: **Romain Girard**, Lauf an der Pegnitz (DE); **Matthias Hartmann**, Forchheim (DE)

(73) Assignee: **PUMA SE**, Herzogenaurach (DE)

(**) Term: **15 Years**

(21) Appl. No.: **29/743,090**

(22) Filed: **Jul. 17, 2020**

Related U.S. Application Data

(60) Continuation of application No. 29/715,969, filed on Dec. 5, 2019, which is a continuation of application No. 29/682,372, filed on Mar. 5, 2019, now Pat. No. Des. 885,724, which is a division of application No. (Continued)

(57) **CLAIM**

The ornamental design for a shoe, as shown and described.

DESCRIPTION

FIG. 1 is a left side perspective view of an ornamental design for a shoe; and,

FIG. 2 is a left side view of the shoe of FIG. 1. The dash-dash-dash broken lines are included for the purpose of illustrating portions of the shoe that form no part of the claimed design.

1 Claim, 2 Drawing Sheets

Related U.S. Application Data

29/621,562, filed on Oct. 10, 2017, now Pat. No. Des. 855,953.
